UNITED STATES PATENT OFFICE.

GEORGE R. WYMAN, OF EAST WALPOLE, MASSACHUSETTS, ASSIGNOR TO
F. W. BIRD & SON, OF EAST WALPOLE, MASSACHUSETTS, A FIRM.

BOX-MACHINE.

SPECIFICATION forming part of Letters Patent No. 731,730, dated June 23, 1903.

Application filed April 6, 1903. Serial No. 151,259. (No model.)

To all whom it may concern:

Be it known that I, GEORGE R. WYMAN, of East Walpole, in the county of Norfolk and State of Massachusetts, have invented certain new and useful Improvements in Box-Machines, of which the following is a specification, reference being had therein to the accompanying drawings.

This invention relates to improvements in machines for turning down and securing the end flaps of a box or carton.

The object of the invention is to mechanically close certain end portions of a box or carton and to apply cement or glue thereto prior to such closing.

Another object of the invention is to so construct a machine of this nature that the flap-closing means shall be controlled by the cement or glue applying means.

Another object of the invention is to so construct a machine of this nature that the flap turning and closing means is automatically set in operation by the prior operation of the glue-applying mechanism and at a certain point in the operation of the glue-applying mechanism.

Another object of the invention is to provide a machine of this nature with means for automatically turning down the flap to which the glue is first applied.

Another object of the invention is to improve the general construction of box-machines of the nature herein described.

The invention consists in a box-machine comprising a flap turning and closing mechanism, a glue-applying mechanism, driving means for such mechanism, and starting means whereby the glue-applying mechanism is first started and the folding and turning mechanism is subsequently put into operation.

The invention also consists in the peculiar construction of the glue-applying means and of its driving mechanism.

The invention also consists in the means for folding down the flap to which glue is first applied.

The invention also consists in such other peculiar features of construction and combination of parts, as shall hereinafter be more fully described, and pointed out in the claims.

Figure 1 represents a front elevation of the

improved box-machine. Fig. 2 represents a side elevation of the same. Fig. 3 represents a vertical sectional view thereof taken on line 4 4, Fig. 1. Fig. 4 represents a vertical sectional view of portions of the carrier-arm shown in relation to the ejector-operating arm. Fig. 5 represents a vertical sectional view of the glue-roll-clutch connections and their actuating-rod. Fig. 6 represents a perspective view of a box for closing the end flaps of which this machine is particularly designed. Fig. 7 represents a detail view of the first folder-plate and its controlling means. Fig. 8 represents a similar view of the clutch connection between the drive-pulley of the main shaft and the sleeve fixed on said shaft, with a portion of the latch for operating the clutch-dog. Fig. 9 represents a vertical sectional view of the machine, taken on line 9 9, Fig. 1. Fig. 10 represents an enlarged detail view of the glue-roll shaft and the mechanism whereby this shaft is connected with and disconnected from the driving-gear. Fig. 11 represents a sectional view of parts of the frame and of the glue-roll shaft and the movable flap-support and turning-plate, the bearing of this flap-supporting plate being shown in relation to the cam-plate on the glue-roll shaft.

Similar characters of reference designate corresponding parts throughout.

This machine is designed for use in closing the open end of a box or carton similar to that shown in Fig. 6, having the end flaps *a a* and *b c*, by turning the flaps *a a* down onto a form, applying glue or cement to the inner surfaces of the flaps *b* and *c*, turning these flaps in succession, the first, as *b*, onto the flaps *a a*, and the second, as *c*, onto the flap, as *b*, subjecting the end of the box formed by these inturned flaps to pressure, and finally ejecting the box from the machine. The flaps *a a* have heretofore been turned inward by hand, the flap *b* being then turned down onto the flaps *a a* by the passage of the glue-roll, which in passing applied glue to the outer surface of the flap *b*. An important object of the present invention is to apply glue to the inner surface of the flap *b*, so that when this flap is turned down onto the flaps *a a* it will adhere thereto and prevent these flaps *a a*

from lifting up at the inside of the box, glue being then applied to the inner surface of the flap *c* to affix that flap to the outer unglued surface of the flap *b*.

5 In the drawings, 5 and 6 represent side or end frames of the machine, these frames being connected at their lower portions by the numbers 7 7 and at the upper portions by the hood or plate 8, of substantial construction, 10 firmly bolted in place and designed to resist a considerable pressure from beneath. Journaled in bearings in these frames and in the bracket 9 is the main shaft 10, and on the shaft is journaled a sleeve having the pulleys 11, 12, and 13 fixed thereto and carrying the belts 14, 15, and 16, the main belt 14 also working over any power-driven pulley (not shown) from which power may be transmitted by said belt to the pulley 11. The hub of the pulley 15 20 has the radial grooves 17, and adjacent to this end of this pulley is the sleeve 18, fixed to the shaft 10 and having a guideway or slot in which the spring-pressed dog 19, having the head 20, may move toward and from the hub of the pulley 11, connecting said sleeve 18 and its shaft 10 with the pulley 11 when 25 engaged in one of said grooves 17, so that the shaft will rotate or by the disengagement of the dog from the pulley-hub to release the shaft 10 from the driving connection with the pulley. On the shaft 10 are fixed the carrier-actuator cam 21, the pressure or lifter cam 30 22, and the ejector-actuator cam 23, Fig. 1. In the frames 5 and 6 is fixed the shaft 24, 35 on which is journaled the sleeve 25 of the carrier-lever 26, the roller-bearing 27 of which rides on the face of the cam 22. This lever has studs 28, on which the arms 29 and 30 of the carrier-arm 31 are journaled, the arm 29 40 having the extension 32, to which is secured the bolt 33, which works through the curved slot 34 in the frame 5 and is secured to one end of the open frame 35, the other end of this frame being furnished with the bearing-sleeve 36, working against the face of the cam 21 and held in contact therewith by the springs 37 37, secured to the upper portions of the arms 29 and 30 and to pins 38, extending from the side frames 5 and 6. The carrier-arm 31 is provided with the adjustable side supports 39 39 and with the axially perforated form 40, which is removably secured to the arm 31. In the rear surface of this arm is formed the recess 41, Fig. 4, and in 55 this recess is movably mounted the ejector-rod 42, having the outwardly-extending ears 43 43 and adapted at times to work through the perforation in the form 40.

Between the frame 6 and the cam 23 is the frame 44, open at its center to work over the shaft 10 and having the stud 45, Fig. 1, working in the groove of said cam. At the rear of the frames 5 6 is mounted the shaft 46, and on this shaft is journaled the sleeve 47, having the lever-arm 49, extending inward and positioned to enter between the ears 43 43 of

the ejector-rod 42 when the carrier-arm 31 reaches its limit of rearward movement.

At the upper portions of the side frames 5 and 6 are inwardly-projecting pivots, as 50, 70 Fig. 3, on which are pivoted the side arms 51 51 of the flap-support and folder-plate 52, furnished with the projecting pin 53, carrying a sleeve, the downward movement of this plate being limited by the finger 54 on the journaled 75 portion of one of the arms 51 coming in contact with the stop 55 on the frame 5 or in any other suitable manner.

To the front portion of the frame 6 is secured the bracket 56, carrying the slide-box 80 57, in which the follower 58 is mounted to reciprocate. In a bearing of this box is journaled the shaft 59, having a pin 60 eccentrically disposed thereon and engaged in the opening of said follower. From the shaft 59 85 extends upwardly the arm 61, connected with the frame member 6 by the spring 62, carrying the rod 63, on which the wiper-plate 64 is mounted to swing, the coiled spring 65 on said rod and fastened to the arm 61 and to the 90 plate 64 being designed to retard the swinging of the plate.

From the frame 6 extends the support 66, in which is journaled the lower portion of the upwardly-inclined glue-roll shaft 67, the upper portion of this shaft being journaled in a bearing 68, supported from the bracket 56. At the upper end of the shaft 67 is secured the glue-roll frame 69, furnished with a horizontal shaft on which the roll-sections 70 are 100 rotatable. At this upper portion of the shaft 67 is also secured the cam 71, having the downwardly-inclined end portions 72 and 73, extending below the point at which the bearing 53 of the plate 52 normally rests and adapted 105 to move under said bearing when said cam rotates with its shaft, whereby said bearing may ride up onto the main surface of said cam when the cam rotates. On the shaft 67, below the bearing 68, is fixed the cam 74, Fig. 110 5, having the collar 75, this cam and its collar being slotted to receive the spring-pressed dog 76, having the projection 77, so that when at its lowest point of movement under the pressure of its spring this dog may extend below the lower surface of the cam 74. 115

The collar 78 is supported from the bracket 56 and forms a bearing for shaft 67. On this collar 78 is supported the bevel-gear 79, loose on the shaft 67 and having the extension 80, 120 furnished in its upper surface with a series of grooves or seats 81, in which the dog 76 may engage when at its lowest point of movement.

In the lower portion of the machine-frame 125 is journaled the treadle rock-shaft 82, furnished at one end with the treadle 83 and at the other end with the lever-arm 84, this arm being bent around the member 6' of the frame 6. On the collar 78 is pivoted the bell-crank 130 lever 85, one of the arms of which is connected with the lever-arm 84 by the connecting-

rod 86, the other arm of this bell-crank lever extending upward and engaging the latch 87, pivoted to the under surface of an arm 88, extending from the bearing 68, this latch having a beveled end adapted to engage the projection 77 of the dog 76 as the dog is carried around by the rotation of the cam 74 and its shaft, so that in riding up this inclined end of the latch 87 the projection 77 lifts the dog 76 out of its engagement with the grooves 81 in the extension 80 of the gear 79, while the swinging outward of the latch 87 by the bell-crank lever 85 releases the projection 77 and permits the dog 76 to be forced downward by its spring.

At the lower portion of the glue-roll shaft 67 is fixed a collar having the cam-finger 89, and on the arm 66 is pivotally mounted the lever 90, having at one end the plate 91, against which the cam-finger 89 may work at times to swing said lever, and at the other end of the lever is mounted for universal movement the upper end of the rod 92, connected with latch 93, which is pivoted on the shaft 82 and has the beveled end 94 for engaging under the projection 20 of the dog 19, so that as the sleeve 18 completes a rotation the projection 20 rides over this beveled end of the latch and is moved outward against the pressure of its spring to release the dog from the groove 17 in the hub of the pulley 11, thus disconnecting this drive-pulley from the sleeve 18.

Embracing the enlarged portion of the sleeve 18 is the friction-strap 95, which exerts a permanent friction on said enlargement to prevent undue movement of the sleeve under the impulse of the drive-pulley 11 and to retard the movement of the sleeve when released from connection with the pulley 11, this friction-strap 95 being held from movement by its engagement with the end of the shaft 82 or in any other suitable manner.

From the rear portion of the frame member 6 extends the bracket 96, in the lower portion of which are bearings in which the shaft 97 is journaled. At one end of this shaft is the pulley 98, over which the belt 15 works, while at the inner end of the shaft is the bevel-gear 99, which meshes with the bevel-gear 79 on the glue-roll shaft 67.

On the bracket 96 is mounted the glue-reservoir 100, having bearings in which the shaft of the glue-supply roll 101 is journaled, the glue-roll shaft being furnished with the pulley 102, over which the belt 16 works, and with the gear 103, which engages with the gear 104, Fig. 2, on the shaft of any usual form of doctor-roll, which is rotatably mounted adjacent to the glue-supply roll 101 and is adapted to distribute the glue evenly over the periphery of said roll in the usual and well-known manner in machines of this class.

When in position to start the operation of the machine, the various parts are in the positions shown in Fig. 1 of the drawings, a box or carton being slipped over the form 40 un-

til its end bears against the adjustable stops 39. The flaps *a a* are bent down by hand until they bear against the surface of the form, 70 the flap *b* turned outward and resting on the sleeve of the flap-turner 64 and the flap *c* resting against the supporting-plate 52, it being understood that power is applied to the pulley 11 by means of the belt 14 and that 75 the belts 15 and 16, with the pulleys 98 and 102 and their related mechanisms, including the bevel-gear 79, are now under operation, while the main shaft 10 and the glue-roll shaft 67 are at rest. Pressure applied to the 80 treadle 83 will cause the rocking of the shaft 82 in its bearings, and the free end of the lever 84 will move downward, drawing with it the rod 86 and swinging the latch 87 out of supporting engagement with the dog 77, 85 which under the pressure of its spring will move into engagement with one of the grooves 81 in the collar of the pulley 79, and as the cam 74, which carries said dog, is fixed to the shaft 67 the shaft 67 and its connected 90 mechanism will rotate with the gear 79. The primary rotation of the shaft 67 effects the swinging of the glue-roll section 70 from the delivery-roll 101 and carries the depressed end 73 of the cam-plate 71 under the bearing 95 53 of the support and folder-plate 52, thus permitting this plate to move down to a point where its upper surface is approximately on a plane with the surface of the form 40. Continuing its rotative movement the shaft 100 67 now carries the glue-sections 70 successively over the inner surface of the flap *b*, over the outer surface of the uppermost of the flaps *a*, and over the inner surface of the flap *c*, and glue is applied thereby to these surfaces. When the application of the glue to the flap *b* is completed, the shaft 67 has made nearly one-half of the complete rotation and is passing above the form 40. During this movement of the shaft 67 the dwell on the 105 face of the cam 74 has held the rod 85 outward against the drawing action of the spring 62 on the arm 61 of the flap-wiper 64. The cut-away portion of this cam 74 being now brought opposite the end of the rod 85 permits this rod to move inward toward the shaft 67 under the action of the spring 62, which draws the arm 61 and its wiper-plate toward the form 40. The wiper-plate turning on its 115 pivot folds the flap *b* down onto the flaps *a a* and wipes across the outer surface of the flap *b* until the outward curve of the cam 74 reaches the rod 85, and this rod is forced backward or outward and through its connections with the arm 62 swinging this arm and its 120 wiper-plate back to its position of rest. During this inward and outward movement of the wiper-plate the glue-roll has passed beyond the edge of the flap *c*, and the depending end 72 of the cam 71 has engaged beneath 125 the bearing 53 of the support and folding-plate 52 and riding under that bearing has caused the swinging upward of the plate 52 to a position to permit the passage thereun-

der of the form 40 with the inturned flaps of the box. At this time the shaft 67, having completed a one-half rotation, the cam 89 at the lower portion of this shaft works 5 against the plate 91 on the pivoted arm 90 and forces that plate outward, thus causing the swinging of the arm 90 and the rod 92 to carry the latch 93 out of its engagement with the portion 20 of the dog 19. The spring 10 working against this dog now forces it along the slot in the sleeve 18 to engage in one of the cross-grooves 17 in the hub of the pulley 11 to connect said pulley with the sleeve 18, and this sleeve being fixed on the shaft 10 15 these parts, with the cams on the shaft, are caused to rotate. The first result of this rotation is to permit the springs 37 to draw backward the carrier until the bearing 36 of the frame rests in the inwardly-curved portion 21^a of the cam 21 to bring the carrier to the position shown in Fig. 3 of the drawings. In this movement the outer surface of the flap c wiping under the edge of the plate 52 this flap is turned down onto the flap b. When 20 the carrier has reached the position shown in Fig. 3, further drawing action of the springs is prevented while the dwell of the cam 21 between the parts 21^a and 21^b is working against the bearing 36. During this period of 25 rest the cam 22 works under the roller-bearing 27 of the lever 26 and lifts the free end of this lever, thus compressing the inturned and glued flaps a, b, and c between the surface of the form 40 and the plate 8 to effect 30 the setting of the glue and securing of the flaps together. When the part 21^b of the cam 21 is brought opposite the bearing 36, the springs 37 act to draw the carrier to its farthest limit of rearward movement and the 35 cam 23 has worked on the pin 45 of the frame 44 to effect the swinging of the arm 49, through its connection with said pin 45, to a position where the free end of this arm will engage between the ears 43 43 of the ejector-rod 42, the 40 further movement of the cam 23 then causing the rapid upward swinging of the arm 49 and the sliding upward of the ejector-rod 42 to lift the box from the form 40 with sufficient impulse to throw the box from the machine. Approximately at the time that the 45 cam 22 is working against the bearing 27 of the lever 26 the glue-roll shaft 67 has completed its rotation, and as this rotation is completed the projection 77 of the dog 76 50 rides up the beveled end of the latch 87, thus lifting the dog 76 from its engagement with the groove in the collar 80 of the gear 79 and disconnecting the shaft 67 from driving connection with said gear, the shaft 67 and its 55 mechanism stopping in the position shown in Fig. 1. After the ejection of the box the cam 21 works to rapidly retract the arm 49 and the ejector-rod 42, so that the carrier 60 may move beneath the plate 8. The throw of the cam 21 now forces backward the bearing 37, thus causing the swinging forward of the carrier to the initial position to receive 65

another box. When this is effected, the shaft 10 has nearly completed a rotation and the projection 20 of the dog 19 rides up the beveled end of the latch 93, this dog being withdrawn from its engagement with the groove in the hub of the pulley 11 to disconnect the shaft 10 therefrom, while the friction-strap 95 acts to resist the undue further movement 75 of the shaft 10.

As the form 40 is readily removable for the substitution of a form of different size, this machine may be used for turning in and securing the end flaps of boxes of various sizes. 80

The wiper-plate 64 is adapted for the use on boxes differing considerably in size and is an important element of this machine, as it effects the turning down of the flap b automatically and intermediate the application of 85 the glue and the turning down of the flap c.

By the use of the automatic means for starting the glue-roll mechanism and for subsequently starting the shaft 10 the operation of the machine is made more rapid and effective, 90 while the automatic stopping of these mechanisms insures against accident to the operator and brings the various parts to rest in the position best suited to the placing of the next box and for starting operations thereon. 95

Having thus described my invention, I claim as new and desire to secure by Letters Patent—

1. A box-machine comprising a carrier adapted to support a box of the nature there-in shown, means for applying glue to one of the box-flaps, and means controlled by connections with the glue-applying means and adapted to follow such glue mechanism to turn down the first flap to which the glue is applied. 105

2. A box-machine comprising a carrier, a glue-roll mounted for movement thereabove, a first flap-folder adapted when at rest to support an associated flap of which the box portion is supported by the carrier, means for driving the glue-roll, and connections between the driving mechanism and the flap-folder whereby, after the application of glue to the flap supported thereby, said folder is actuated to fold the flap down onto flap supported by the carrier. 115

3. A box-machine comprising a drive-shaft adapted to be continuously driven, a glue-roll support rotatably mounted adjacent thereto, 120 and means adapted to be automatically released upon a complete rotation of the glue-roll support for connecting said drive-shaft and glue-roll support.

4. A box-machine comprising a drive-shaft 125 adapted for continuous driving, a glue-roll support rotatably mounted, releasable means for connecting the glue-roll support with the drive-shaft during a single rotation of the glue-roll support, a carrier, and a first folder-plate mounted to swing, and means for controlling the swinging of the folder-plate from the glue-roll support. 130

5. A box-machine comprising a glue-roll

support rotatably mounted, a gear loose thereon, a clutch for connecting said gear and shaft, means for releasing the clutch after a single rotation of the gear, and a drive-shaft having 5 a gear meshing with the gear of the glue-roll support.

6. A box-machine comprising a glue-roll support rotatably mounted, a gear loose thereon, a clutch fixed on said support and adapted 10 to engage said gear, a latch adapted to intercept said clutch mechanism, to release the same from the gear, at the completion of a single rotation, and a drive-shaft having a gear meshing with the gear of the glue-roll 15 support.

7. A box-machine comprising a glue-roll support, or shaft, rotatably mounted, a cam on said support, a rod, in the nature of a follower, reciprocal in bearings, against which 20 the cam works, an arm pivotally mounted and connected with said rod by a crank, a spring acting on said arm, and a wiper, or folder plate, pivotally mounted on said pivot.

8. A box-machine comprising a glue-roll support rotatably mounted, a box-carrier, a controlling and driving mechanism for the carrier, an independent driving mechanism, and means controlled by the glue-roll support for connecting the independent driving 30 mechanism with the driving means of the carrier.

9. A box-machine comprising a carrier pivotally mounted, a shaft journaled in bearings, means on said shaft for controlling and operating the carrier, a driving mechanism rotatably mounted on said shaft, a clutch for connecting said driving mechanism, a glue-applying mechanism, and connections between 35 said glue-applying mechanism and said 40 clutch.

10. A box-machine comprising a pivoted lever, a carrier pivotally mounted on the lever, springs for moving the carrier in one direction, a frame connected with the carrier and 45 having a bearing, a shaft furnished with cams working respectively against said bearing and against said lever, a driving mechanism rotatable on said shaft and furnished with means for connecting the same with the shaft 50 at times, a glue-applying means, and connections actuatable by the glue-applying means for operating said clutch.

11. A box-machine comprising a carrier, a glue-applying device, an upwardly-extending rotatable shaft on which the glue-applying 55 device is mounted, means for rotating said shaft, driving means for the carrier, operating and controlling means therefor, and mechanism adapted to be actuated by the 60 shaft of the glue-applying device after the

movement of said device over the carrier for connecting the carrier operating and controlling means with its driving means.

12. A box-machine comprising a glue-roll shaft journaled in bearings, a carrier, operating and controlling means for the carrier, driving means therefor, a cam on the glue-roll shaft, a pivoted arm adapted to be actuated by said cam, a clutch connection between the driving means and the operating means 65 of the carrier, and a connection between said pivoted arm and said clutch for releasing the clutch at the completion of the operation of the carrier.

13. In a box-machine, the combination with 75 a suitable carrier, of the arm 61 furnished with the rod 65, the folder-plate 64 pivotally mounted on said rod, and means for controlling and operating said arm 61.

14. In a box-machine, the combination with 80 the glue-roll shaft 67 rotatably mounted, the cam 74 on said shaft, the rod 58 mounted to reciprocate in contact with said cam, the shaft 59 journaled in bearings and having the crank connection with the rod 58, the arm 61 85 mounted on the shaft 59 and furnished with the spring 62, the pivot 63 extending from said arm, and the plate 64 pivotally mounted on said pivot.

15. In a box-machine the combination with 90 the glue-roll shaft 67 rotatably mounted, the gear 79 free on said shaft, and the shaft 97 the gear 99 of which meshes with the gear 79, of the sleeve on the shaft 67, the dog mounted to move in said sleeve and to engage in one 95 of the grooves in the gear 79, the latch 87 pivotally mounted adjacent to the shaft 67 and adapted to engage said dog to release it from its engagement with the pulley 79, and means for actuating the latch 87. 100

16. The combination with the shaft 67 rotatably mounted, driving means adapted to be connected with said shaft at times, and the cam 89 secured to said shaft, of the shaft 10, a sleeve loosely mounted on the shaft and 105 carrying the pulley 11 having the grooves 17 in its hub, and the sleeve 18 fast on said shaft and furnished with the dog 19, of the latch 93 pivotally mounted and adapted to engage said dog, the rod 92 secured to said latch, and the arm 90 pivotally mounted in relation to the cam 89, and pivotally connected with the upper end of the arm 92, as and for the purpose described. 110

In testimony whereof I affix my signature 115 in presence of two witnesses.
